UNITED STATES PATENT OFFICE.

ERICH WERWATH, OF LINDEN, NEAR HANOVER, GERMANY.

AIR-INJECTOR.

No. 903,646.

Specification of Letters Patent.

Patented Nov. 10, 1908.

Application filed May 31, 1906. Serial No. 319,560.

To all whom it may concern:

Be it known that I, ERICH WERWATH, of Linden, a subject of the King of Prussia, and whose post-office address is No. 1^A 5 Stephanusstrasse, Linden, near Hanover, Prussia, German Empire, have invented a new and useful Air-Injector, of which the following is a specification.

This invention relates to air-injectors operated by means of steam or other working fluids, and more particularly to such injectors as are used in combination with boiler furnaces for the purpose of supplying the latter for some time with air above the 15 freshly charged layer of fuel, the injector being stopped when the fire appears on the surface of the fuel. As well known, the actual practice is to combine the said injector with means dependent upon, or controlled by, the fire-door in such a manner that the act of opening the latter has the effect of connecting the injector with a steam-supply or other working-fluid-supply, said supply being stopped again by the act 25 of re-closing the fire-door. In this combination the injector is left in free communication with the atmosphere during the periods of its rest, that is to say when the fire-door is closed and consequently there is no supply 30 of steam or other working fluid. This has the effect that the draft of the chimney acts to suck in air through the injector, so that a certain supply of air to the zone above the fire is continued. Now such continued supply 35 or air to the zone above the fire has the effect of rendering the combustion uneconomical for the reason that this air does not assist the combustion-process but attenuates the combustion-gases and thereby weakens 40 the draft of the chimney.

It is the object of the present invention to do away with the inconvenience above explained.

To this end, my invention provides, in 45 combination with the injector and the means for supplying the same with the working fluid, means under the control of the working fluid for opening and re-closing the air-inlet of the injector, so that said opening 50 will be automatically closed by the act of stopping the working-fluid supply, and automatically re-opened by the act of starting the said supply. And in order that my present invention may be fully understood 55 I proceed to describe the preferred form of

practicing the same, reference being had to the annexed sheets of drawings of which

Figure 1 is a vertical central section of the apparatus with its movable parts in the position they take during the periods of 60 rest, and Fig. 2 a similar section showing the movable parts in the position they take after the supply of steam has been started.

In both figures similar reference letters are used to indicate identical parts, the furnace, its connection with the apparatus and the steam supply for the latter being omitted.

a is a cylindrical box provided at one end with an air-inlet *a*¹ and communicating through its opposite end *a*² (the outer portion of which is broken away) with the furnace not shown. In the axial line of this box is arranged a cylindrical chamber *b* open at top and bottom and having an opening *b*¹ in its side through which it communicates with a pipe *b*² penetrating through the side wall of the box *a* and communicating with a steam supply not shown. In the example illustrated the chamber *b* and its supply-pipe *b*² are shown as cast into one piece. In the 70 top-opening of the chamber is fixed the receiving end of the nozzle *c*, and in the bottom-opening is secured the inner open end of a cylindrical extension *d* having in its bottom an axially placed opening *d*¹. Within 75 the chamber *b* and its extension *d* is arranged a hollow cylindrical slide or piston *e* which tightly fits to the inner wall of the extension *d*. The top of the piston is closed and formed with a short extension *e*¹ of a smaller 80 diameter. Within the piston and in the axial line thereof is arranged a cylindrical stem *f* the inner end of which is secured to the top of the piston, and the other end of which projects through the opening *d*¹ in 85 the bottom of the extension *d*, the stem tightly fitting into said opening. Within 90 the piston the stem *f* is surrounded by a spiral spring *g* one end of which bears against the inner top wall of the piston *e*, while the other end bears against the bottom of the extension *d*. To the outer end 95 of the stem *f* is fixed a plate or disk *h* having a somewhat larger diameter than the air-inlet *a*¹ of the box *a*. The length of the stem *f* is such that when it is in the position shown in Fig. 1, the disk *h* is pressed upon the air-inlet *a*¹, which may be provided with a recessed portion *a*³ (Fig. 2) to form a seat 100 for the said disk. Moreover in this position 105

110

of the parts the piston *e* bears with its extension *e*¹ against the inner end of the nozzle *c* thereby closing the latter and leaving a portion *i* of the chamber *b* in communication 5 with the steam supply pipe *b*².

Suppose the piston *e* be in the position shown in Fig. 1 and steam be supplied through pipe *b*². The steam penetrates into the portion *i* of the chamber *b* and by its 10 pressure upon the top of the piston shifts the latter back against the resistance of the spring *g* which is compressed. This shifting back of the piston has the effect of simultaneously withdrawing the extension *e*¹ 15 of the piston from the nozzle *c* and the disk *h* from the air-inlet *a*¹ so that a steam jet issues from the nozzle into the portion *a*² of the box *a* and air is drawn into the latter through its opening *a*¹ and supplied to the 20 furnace in well known manner. The parts of the apparatus are then in the position shown in Fig. 2 and are withheld in this position as long as the steam pressure is 25 strong enough to maintain the spring *g* in its compressed state. As soon, however, as the steam pressure is weakened to such an amount as will be overcome by the tension of the spring, the latter will reëxpand and in doing so it drives the piston forward into 30 its starting position whereby the disk *h* is re-closed upon the air inlet *a*¹, and the extension *e*¹ of the piston upon the inner or receiving opening of the nozzle *c*.

I prefer to so bevel the edge of the piston-extension *e*¹ that it can penetrate to some extent into the receiving opening of the nozzle and tightly close the same for the purpose of preventing useless escape of steam after closure of the air-inlet *a*¹ and of 35 insuring that on starting the steam supply the incoming steam is caused to act with its full pressure upon the piston. The lower edge of the piston may also be provided with a bevel to coöperate with a corresponding 40 circumferential incline at the bottom of the extension *d* for preventing escape of steam along the stem *f* when the piston is 45 in its lower position as in Fig. 2.

Instead of a disk plate or lid as *h*, any 50 other convenient closing means may be used that are adapted to be controlled by the strokes of the piston *e*, such as throttle valves and the like. I therefore wish it to be understood that the term lid as used in 55 the annexed claims is intended to comprise all forms and kinds of closing means or devices adapted for the present purpose.

Obviously instead of steam compressed air and other suitable gases, and even water may 60 be used as the working fluid and I therefore wish it to be understood, that my present invention shall not be bound to the use of steam as the working fluid.

What I claim, and desire to secure by Letters Patent of the United States, is:—

1. The combination with the injector-nozzle, a box therefor having an air-inlet and air-outlet, and a pipe for supplying the nozzle with the working fluid, of a lid adapted to close the air-inlet of said box, a piston connected with the lid, and a chamber closely surrounding the piston and communicating with the said supply pipe, whereby said air-inlet is opened upon admission of working fluid to the injector-box, substantially as and for the purpose specified. 70

2. The combination with the injector-nozzle, a box therefor having an air-inlet and air-outlet, and a pipe for supplying the nozzle with the working fluid, of a chamber intermediary and communicating with the nozzle and the pipe, a piston within the chamber, a lid adapted to close the air-inlet of the box, a connection between the lid and the piston, whereby admission of working fluid to the nozzle acts on said piston to open said air-inlet, and means for automatically returning the piston to its starting position when the supply of working fluid is cut off, substantially as and for the purpose specified. 80

3. The combination with the injector-nozzle, a box therefor having an air-inlet and air-outlet, and a pipe for supplying the nozzle with the working fluid, of a chamber intermediary and communicating with the nozzle and the pipe, a hollow piston within said chamber closed at its inner end and open at its outer end, a stem axially arranged within the piston and fixed to the inner end of the same, said intermediary chamber having an opening for the piston to project through, a lid fixed to the lower end of the stem and adapted to close the air-inlet of said box, whereby admission of working fluid to the nozzle acts on said piston to open said air-inlet, and means for automatically returning the piston to its starting position, substantially as and for the purpose specified. 95

4. The combination with the injector-nozzle, a box therefor having an air-inlet and air-outlet, and a pipe for supplying the nozzle with the working fluid, of a chamber intermediary and communicating with the nozzle and the pipe, a hollow piston within the chamber closed at its inner end and open at its outer end, a stem axially arranged within the piston and fixed to the inner end of the same, means whereby the piston normally closes the nozzle, a lid fixed to the outer end of the stem and adapted to close the air-inlet of said box, and a spiral spring encircling said stem within the hollow piston and interposed between the inner end of the piston and the outer end of its inclosing chamber, substantially as and for the purpose specified. 115

5. The combination with the injector-nozzle, a box therefor having an air-inlet and 120

- air-outlet, and a pipe for supplying the nozzle with the working fluid, of a chamber intermediary and communicating with the nozzle and the pipe, a hollow piston within 5 the chamber closed at its inner end and open at its outer end, a stem axially arranged within the piston and fixed to the inner end of the same, an opening in the outer end of the intermediary chamber for the piston to 10 project through, a lid fixed to the outer end of the stem and adapted to close the air-inlet of said box, means for automatically returning the piston to its starting position, and means connected with the piston for closing 10 the receiving opening of the nozzle, substantially as and for the purpose specified.
6. The combination with the injector-noz-
zle, a box therefor having an air-inlet and air-outlet, and a pipe for supplying the nozzle with the working-fluid, of a spring-actuated piston having means for closing the entrance to the nozzle, and a lid operated thereby for closing said air-inlet, whereby admission of working-fluid under sufficient pressure to overcome the spring will act on 20 said piston to open the entrance to said nozzle and open said air-inlet.
